UNITED STATES PATENT OFFICE.

MAURICE S. FINCH, OF ST. JOSEPH, MISSOURI, ASSIGNOR TO SPECIALTY SHOE MACHINERY COMPANY, OF ST. JOSEPH, MISSOURI, A CORPORATION OF MISSOURI.

ADJUSTABLE ANVIL FOR SHOE-NAILING MACHINES.

1,191,682.

Specification of Letters Patent. Patented July 18, 1916.

Application filed April 5, 1915. Serial No. 19,196.

To all whom it may concern:

Be it known that I, MAURICE S. FINCH, a citizen of the United States, residing at St. Joseph, in the county of Buchanan and State of Missouri, have invented certain new and useful Improvements in Adjustable Anvils for Shoe-Nailing Machines, of which the following is a specification.

My invention relates to shoe machinery and more particularly to anvils for use in connection with shoe nailing machines.

The particular object of my invention is the provision of an anvil for this type of machine that is capable of adjustability whereby a change may be quickly made from a short nail to a large nail or vice versa. As is well-known to those skilled in this art, the anvil moves upwardly and meets the nail while the latter is being driven and the motive for actuating the nail-driving mechanism is usually common to the anvil plunger or rod, both mechanisms being operable by means of a single foot-treadle in manually operated machines.

With this in mind, it is also an object of my invention to provide means for adjusting the anvil or its rod without affecting the nail driving mechanism.

A still further object is to construct the adjusting devices in as simple a manner as possible so that it is easily and quickly operated for nails of different sizes or for driving or clenching the nails at different depths in the sole or heel of the shoe. And lastly, it is an object of my invention to provide an anvil with adjusting means that are economical to manufacture and do not materially add to the cost of the machine to the user.

These objects I prefer to accomplish by the means and in the manner hereinafter fully described and as more particularly pointed out in the claims, reference being had to the accompanying drawings forming a part of this specification wherein similar reference characters indicate the same parts in the various figures.

In the drawings:—Figure 1 is a side elevation of the standard of a well-known shoe nailing machine having a portion of the casting broken away to disclose my invention applied to the anvil thereof; Fig. 2 is a fragmentary vertical section, drawn to a larger scale showing in detail the adjusting elements; Fig. 3 is a transverse horizontal

section on line 3—3 of Fig. 2, and Fig. 4 is an enlarged detail of the particular locking pawl employed in connection therewith.

Referring to the drawings, and more particularly Fig. 1 thereof, it will be observed A represents a suitable hollow standard that is preferably rectangular shaped in horizontal section having its lower edges flared outwardly to form a basal flange and provided at its upper end with frustum-shaped extensions B and C. The former of these extensions (B) affords bearings for journaling the upper portion of the vertically disposed operating plunger D of the nail driving mechanism while the latter extension (C) journals the upper portion of the vertically reciprocable rod 5 upon the upper extended end of which the anvil 6 is supported. This anvil rod 5 has its lower end journaled in an L-shaped bearing bracket 7 secured to and projecting laterally from the inner surface of the adjacent wall of the standard, and mediate these bearings said rod is tapped transversely by a cross pin 8 for supporting a coiled expansion spring 9 surrounding the rod between said pin and its upper bearings.

Mounted in axial alignment below supporting rod 5 is an adjustable rod 10 slidably journaled in bearings 12 secured laterally to said standard wall. Said adjustable rod 10 is preferably provided at its lower end with bifurcations 13 that are adapted to pass upon each side of and be secured to a substantially L-shaped foot lever 14 by means of a cross-pin 15, which foot lever is pivoted at the angle of its larger and shorter arms to a pair of parallel lateral ears 16, 16, projecting from the exterior of the standard on each side of a transverse slot 17 formed therein. The foot lever preferably extends transversely across the interior of the standard so that its inner end is adjacent a vertically elongated slot 20 in the opposite wall thereof where said treadle is provided with an enlarged head 21 from which two parallel lateral studs 22 and 23 project. A segmental shaped plate 24 is secured to the outer surface of the standard wall surrounding the slot 20 and said plate is provided with a vertically elongated slot 25 one of the sides of which is provided with a double row of ratchets or teeth 26, arranged in alternate relation to each other.

Stud 22 above mentioned has two pawls 110

27 pendently mounted thereon that are kept normally in engagement with said teeth by suitable springs 28 while the foot lever itself is forced toward the teeth by a flat leaf 5 spring 29 secured to its end and projecting into said slot 25 so that it bears against the edge opposite said teeth.

The pivotal bolt 18 upon which the foot lever is fulcrumed is preferably consider- 10 ably smaller in diameter than the opening 19 in the lever arm so that the lever may be rocked laterally as indicated in dotted lines in Fig. 3, for the purpose of rotating the pin 23 about the pin 22 as its axis, thereby caus- 15 ing the pin 23 to contact the shoulder of the pawl 27 (Fig. 4) pulling it out of engagement with the ratchet teeth 26 and thereby permitting of the adjustment of the rod 10.

The upper end of adjusting rod 10 is pref- 20 erably provided with a collar 30 that is rigidly secured thereto and is provided with a suitable bifurcated bracket 31 that affords a fulcrum for a bifurcated link 32 that has its shorter hooked end 33 terminating below 25 and in engagement with the lower end of anvil rod 5. The bifurcations of link 32 are adapted to pass on each side of plunger shaft D and are pivotally mounted in the upper ends of a vertically disposed substantially 30 Y-shaped link 34 that has its lower end pivotally mounted in a lateral lug upon a collar 35 surrounding the plunger shaft D.

From the above it will be seen that by de- 35 pressing foot lever 14 the adjusting rod 10 will be forced upwardly thereby raising the adjacent end of bifurcated link 32 and correspondingly elevating the anvil rod and anvil engaging the hooked end of said link. And when the plunger D is depressed to 40 operate the nail drive mechanism the link 32 will be rocked on its fulcrum and its hooked end 33 will raise the anvil rods and anvil to meet the nails. It will be also understood that the operating movement of the anvil is 45 relatively the same distance whether the anvil has been adjusted closer to or farther away from the nail inserting mechanism, the adjustment being for the purpose of accom- 50 modating soles of different thicknesses or for nailing brads of divers lengths.

While I have illustrated and described certain specific means for carrying out my invention it, of course, will be obvious to others skilled in the art to which the same 55 pertains that various changes and modifications may be made therein without materially departing from the spirit of my invention, and I desire it understood that all such refinements and modifications are in- 60 cluded within the scope of my invention as set forth in the appended claims.

Having thus described my invention, what I claim as new and desire to secure by Letters Patent, is:—

,65 1. In a shoe-nailing machine an anvil

mounted upon a vertically reciprocal rod, means for reciprocating same comprising a spring engaging said rod and adapted to move the same to the limit of its downward movement, and a lever adapted to move the 70 rod in its upward direction against said spring, and independent means for vertically adjusting the fulcrum of said lever.

2. In a shoe nailing machine an anvil, a vertically reciprocal rod upon which the 75 same is mounted, a spring engaging said rod and adapted to move the same to the limit of one of its movements, a lever for moving said rod against said spring, and devices for vertically adjusting the fulcrum of said 80 lever.

3. In a shoe nailing machine, an operating shaft, an anvil, a vertically reciprocal rod upon which said anvil is mounted, a spring engaging said rod and adapted to move the 85 same to the limit of one of its movements, a lever operatively connected with said shaft at one end and having its opposite end engage the lower end of said rod, a vertically disposed rod below said anvil rod and upon 90 the upper end of which said lever is fulcrumed, and means for adjusting said last mentioned rod and thereby raising or lowering the fulcrum of said lever.

4. In a shoe nailing machine, an operating 95 shaft, an anvil, a vertically reciprocal rod upon which said anvil is mounted, a spring engaging said rod and adapted to move the same to the limit of one of its movements, a lever operatively connected with said shaft 100 at one end and having its opposite end engage the lower end of said rod, a vertically disposed rod below said anvil rod and upon the upper end of which said lever is fulcrumed, and a foot lever to which the lower 105 end of the last mentioned rod is connected for adjusting said last mentioned rod and thereby raising or lowering the fulcrum of said lever.

5. In a shoe nailing machine, an operating 110 shaft, an anvil, a vertically reciprocal rod upon which said anvil is mounted, a spring engaging said rod and adapted to move the same to the limit of one of its movements, a lever operatively connected with said shaft 115 at one end and having its opposite end engage the lower end of said rod, a vertically disposed rod below said anvil rod and upon the upper end of which said lever is fulcrumed, and means for adjusting said lower 120 rod consisting of a foot lever to which the same is pivotally connected, pawl and ratchet mechanism for locking said foot lever in its adjusted positions, and means for disengaging said pawl and ratchet mech- 125 anism.

6. In a shoe nailing machine, an operating shaft, an anvil, a vertically reciprocal rod upon which said anvil is mounted, a lever operatively connected with said shaft at one 130

end and having its opposite end engage the lower end of said rod, a vertically disposed rod below said anvil rod and upon the upper end of which said lever is fulcrumed, and 5 means for vertically adjusting said lower rod consisting of a substantially L-shaped foot-lever fulcrumed mediate its ends and connected to said lower rod mediate the ends of its horizontal arm, escapement devices 10 operable upon the outer end of said horizontal arm and means for releasing said escapement devices.

7. In a shoe nailing machine, a suitable standard an operating shaft vertically reciprocal therein, an anvil and spring pressed anvil rod mounted adjacent to and parallel with said shaft, a spring engaging said rod and adapted to move the same to the limit of one of its movements, a lever operatively 20 connecting said shaft and rod, and means for adjusting the fulcrum of said lever in a vertical direction, consisting of a vertically reciprocal rod arranged in axial alinement with said anvil-rod, a fulcrum for said lever upon the upper end of said reciprocal rod, and a foot lever 25 fulcrumed mediate its ends to said standard and pivotally connected to the lower end of said reciprocal rod, a pawl carried by the end of said foot lever, and a ratchet in the adjacent wall of the standard adapted to be engaged by said pawl for locking said foot- lever in its adjusted positions.

In testimony whereof I affix my signature in the presence of two witnesses.

MAURICE S. FINCH.
